United States Patent Office

Des. 194,130
Patented Nov. 20, 1962

194,130

DOLL PACKAGE

Amram Haddad, New York, N.Y.
(43-12 50th St., Woodside 77, N.Y.)

Filed Dec. 28, 1961, Ser. No. 68,102

Term of patent 14 years

(Cl. D58—2)

FIG. 1

FIG. 2

FIG. 1 is a front elevational view of a doll package showing my new design. The broken line showing of the doll in FIGURE 1 is for illustrative purposes only.

FIG. 2 is a top plan view thereof.

FIG. 3 is a bottom plan view thereof.

I claim:

The ornamental design for a doll package, as shown and described.
